(57) **CLAIM**

The ornamental design for an item holder, as shown and described.

DESCRIPTION

FIG. 1 is a top, front right side perspective view of an item holder according to the design in a connected configuration; the top, front left side perspective view is a mirror image of FIG. 1;

FIG. 2 is a rear plan view of the item holder of FIG. 1; FIG. 3 is a front plan view of the item holder of FIG. 1; FIG. 4 is a right side elevation view of the item holder of FIG. 1;

FIG. 5 is a left side elevation view of the item holder of FIG. 1;

FIG. 6 is a top plan view of the item holder of FIG. 1; FIG. 7 is bottom plan view of the item holder of FIG. 1;

FIG. 8 is a front plan view of the item holder of FIG. 1 in use on a vehicle sun visor;

FIG. 9 is a rear plan view of the item holder of FIG. 1 in a disconnected configuration;

FIG. 10 is front plan view of the item holder of FIG. 1 in the disconnected configuration;

FIG. 11 is a top, front right side perspective view of an item holder according to a variation of the design in a connected configuration; the top, front left side perspective view is a mirror image of FIG. 11;

FIG. 12 is a rear plan view of the item holder of FIG. 11; FIG. 13 is a front plan view of the item holder of FIG. 11; FIG. 14 is a right side elevation view of the item holder of FIG. 11;

FIG. 15 is a left side elevation view of the item holder of FIG. 11;

FIG. 16 is a top plan view of the item holder of FIG. 11;

FIG. 17 is bottom plan view of the item holder of FIG. 11; FIG. 18 is a front plan view of the item holder of FIG. 11 in use on a vehicle sun visor;

FIG. 19 is a rear plan view of the item holder of FIG. 11 in a disconnected configuration; and,

FIG. 20 is front plan view of the item holder of FIG. 11 in the disconnected configuration.

The broken lines illustrate portions of the item holder that form no part of the claimed design.

1 Claim, 10 Drawing Sheets
